UNITED STATES PATENT OFFICE.

THOMAS YELCIC, OF REPUBLIC, PENNSYLVANIA, ASSIGNOR OF ONE-HALF TO GEORGE VERBONIC, OF REPUBLIC, PENNSYLVANIA.

RAILROAD-CROSSING SIGNAL.

Application filed July 1, 1925. Serial No. 40,755.

To all whom it may concern:

Be it known that I, THOMAS YELCIC, a subject of the King of Jugoslavia, residing at Republic, in the county of Fayette and 5 State of Pennsylvania, have invented certain new and useful Improvements in Railroad-Crossing Signals, of which the following is a specification.

This invention relates to railroad signals 10 and more in particular to railroad crossing signals.

One of the main objects of this invention is to provide a signaling system for railroad crossings which will give warnings to the 15 public a considerable time before a railroad train reaches the crossing. Another object of this invention is to provide a signaling device that will set itself again into normal or neutral position after the train has passed 20 the crossing. A further object is to provide a signaling apparatus which has warning signs adapted to appear only at the approach of a train and to disappear from view after the train has passed. Still a further object 25 is to provide a signaling device which can be applied satisfactorily for crossings having a single track as well as for such with several tracks, and which will operate regardless of the direction of travel of the 30 trains. Yet another object is to provide a signaling apparatus which is positive in operation, simple in construction and installation. Additional features and advantages 35 of this invention may appear from the following description considered in connection with the accompanying drawing forming part of this application, and in which:

Fig. 1 is a diagrammatic view showing the general embodiment of my invention for 40 a railroad crossing having two tracks.

Fig. 2 is a side elevation of the principal operating mechanism of my signaling device.

Fig. 3 is a front elevation of Fig. 2, showing 45 also a part of the track bed construction.

Fig. 4 is a side elevation of a so-called strike-arm used in connection with this signaling system and intended to be installed on the locomotive or tender of the trains.

50 Fig. 5 is a front elevation of Fig. 4.

Fig. 6 is a front elevation of an oscillating disc signal used in this invention.

Reference being had to the drawing, the 55 operating mechanism of my invention consists of sets of bell-crank-levers 1 placed ad-

jacent the track a considerable distance of and at both sides of the railroad crossing; each bell-crank-lever having a vertical arm 2 and a horizontal arm 3 united to a central hub 4 provided with gear teeth 5 on its periphery. The bell-crank-levers of each set are securely mounted on a common shaft 6 which is mounted for rotation in standards 7 comprising two parallel bearing supports 8 formed integrally with the base 9, the front and rear stops 10 and 11 which limit the movements of the bell-crank-levers, and a vertical post 12, the purpose of which will be described later. Suitable bolts 13 are used to secure each standard to a wooden base or 70 tie 14.

Disposed beneath each bell-crank-shaft 6, in parallel relation thereto and mounted for rotation in suitable bearings 15 provided in the bearing supports 8 is the rack-shaft 16 75 upon which are fastened the segmental spur-gears 17 adapted to mesh with the teeth on the bell-crank-levers. At one end of this shaft is keyed, or otherwise secured, the spur gear 18 which meshes in a suitable rack 19 80 provided at each end of the pull-rod 20 which runs parallel to the tracks between both sets of operating mechanisms and by means of which the latter are operated simultaneously. As shown in Fig. 1, and for 85 reasons to be explained later, these racks are disposed on opposite sides of the pull-rod. To reduce friction, the latter is preferably mounted on rollers 21 suitably spaced throughout its whole length. 90

At the crossing are set on each side of the railroad tracks two posts 22 connected at their tops by the parallel cross-beams 23 at the middle of which is provided a box-like enclosure 24 in which are mounted the electric bell 25, the electric motor 26, the oscillating disc signal 27 and a movable sign, such as the representation of a watchman 28. The oscillating signal 27 is operated by the motor by means of a crank 29 mounted on the motor-shaft, and the connecting rod 30 which connects the arm 31 of the oscillating signal with said crank. 100

This signal is rockably mounted on a pin 32 and comprises also a vertical arm 33 having at its lower end the target-like disc 34, preferably provided at its center with an electric light 69 that is operated by means of the electrical wires 70 connected to the same electric circuit as the motor and the 110

bell. At the upper end of the vertical arm is a counterweight 35 the purpose of which is to equalize the weight of the oscillating disc and thus reduce the load on the motor.

5 Mounted on the pull-rod 20 is an arm 36 at the end of which is provided the electrical contact-clip 37 to which is connected the end 38 of the electrical conductor 39. This contact-clip is disposed to engage a 10 stationary contact-plug 40 to which is connected the other end 41 of the conductor 39.

The movable figure 28 is operated mechanically by the pull-rod 20 by means of a bell-crank-lever 42 rockably mounted on 15 the bracket 43 secured to one of the posts. The lower end of the vertical arm 44 of this lever is slotted to engage a pin 45 secured in the pull-rod, and the horizontal arm 46 is hingedly connected by means of the pin-connection 47 to a vertical rod 48 which is guided and supported on one of the posts by means of the guides 49. At the upper 20 end of this rod is a pin-connection 50 by means of which is operated the upwardly bent lever 51 having one end fulcrumed in a bearing 52 secured to the post and supporting at the upper end the hingedly mounted figure 28. The latter is suspended above its center of gravity in order to 25 always maintain a vertical position, regardless of the inclination of its supporting lever.

The operating bell-crank-levers 1 are actuated by means of a special strike-arm 35 35 which must be mounted suitably on the under-frame 54 of each locomotive or tender traveling on the railroads provided with my signaling system. This strike-arm is composed of an upper member 55 and a lower member 56 which are hingedly connected together by means of the pin and knuckle connection indicated by the numeral 57. A spring 58 is used to maintain both members normally in vertical alinement. The 40 strength of this spring must be such that it will enable the strike-arm to rotate the operating bell-crank-levers and connected parts while, on the other hand, it will allow the lower member of the strike-arm to 45 swing over unyielding obstacles. The upper member has at the top an enlarged portion 59 in which are provided apertures 60 for the insertion of bolts 61 to secure the strike-arm to the engine or tender frame. The lower member is preferably provided 50 at its lower end with a bulbous enlargement 62 which serves as the striking head for the strike-arm.

55 On the operating shaft 6 is securely and 60 suitably mounted a crank 63 having a pin 64 to which is attached one end of the helical spring 65, the other end of which is attached to a threaded eye-bolt 66 which is adjustably secured in the post 12. The 65 purpose of this crank and spring mechanism

is to complete the quarter turn rotation of the operating bell-crank-levers which was begun by the strike-arm. As will be readily understood by referring to the drawing, the strike-arm is not adapted to rotate the bell-crank-lever full 90 degrees because it strikes the latter at a point above the center of rotation and thus leaves the bell-crank-lever after it has rotated approximately 45 to 50 degrees. The position of the crank and of the point of attachment of the spring must be so selected that the uncompleted rotation of the bell-crank-lever is effected by the spring. The purpose of the front and rear stops 10 and 11 is to 70 limit the amount of rotation of the bell-crank-lever to substantially 90 degrees. 75

The method of operation of my system may now be succinctly described; it is as follows: Assuming that a train be coming from the left side, in Fig. 1, the strike-arm 53 on the locomotive will come in contact with the upper arm 2 of the operating bell-crank lever 1 and, with the assistance of the spring 65, will rotate the same in a clockwise sense until said upper arm strikes the rear stop 11. This rotation will cause a counter-clockwise rotation of the rack-shaft 16 at the left side of the crossing and a left to right horizontal movement of the pull-rod 20. Owing to the reversed arrangement of the rack 18 and the rack-gear 19 at the right end of the pull-rod, the right hand rack-shaft 16 will be rotated in a clockwise sense and the operating bell-crank-levers 1 counter-clockwise so that the horizontal arm 3 will now assume a vertical position. After the train has passed the crossing, the strike-arm on the locomotive strikes the now vertical arm 3 of the right hand operating bell-crank-lever 1, thereby causing all the bell-crank-levers and the pull-rod to assume their original or normal position. It will also be seen from Fig. 1 that the first movement of the pull-rod will cause the movable effigy of the watchman to appear below the enclosure 24 and also close the contact between the movable contact-clip 37 and the stationary contact-block 40, thus establishing a current of electricity whereby the bell, the motor, the oscillating signal and the electric light thereof become operative to call the attention of the public. 90 95 100 105 110 115

If two trains should follow each other closely, or if two trains traveling in opposite directions should cross each other at or near the railroad crossing, it will be readily seen from Fig. 1 that once the signaling device has been set by the first train, it will remain in that position until said train has passed beyond the other set of operating bell-crank-levers. The strike-arms of all subsequent trains being simply folded backwards as they strike the upstanding arms of 120 125 130

the bell-crank-levers, a further rotation of which would, at the present time, be prevented by the stops 10 or 11.

- It is evident that the bell-crank shafts 6 and the rack-shafts 16 must be mounted below the railroad tracks; for this reason these parts and their supports are installed in suitable transverse trenches 67 suggested in dot and dash lines in Fig. 1. This construction also requires that the pull-rod be similarly installed in a longitudinal trench 68 which would, of course, be bridged over at the road crossing proper, to permit safe travel on the public highway.
15. It will be understood, of course, that the arrangement I have herein shown is merely suggestive of many that might be adopted in carrying out my invention, and I do not wish to be limited to the construction illustrated otherwise than as specified in the appended claims.

I claim:

1. A railroad crossing signaling apparatus comprising a set of bell-crank-levers positioned at each side of said crossing and adapted to be operated by a strike-arm positioned on a passing train; a rack-gear actuated by each of said bell-crank-levers; a pull-rod running parallel to the railroad track and having at each end a rack to be engaged by one of said rack-gears; electrical switching means operated by said pull-rod adapted to open and close an electrical circuit to an electric-bell, an electric motor and lights; mechanical means also actuated by said pull-rod and adapted to operate a visible warning signal; said sets of bell-crank-levers being disposed to rotate simultaneously and in opposite directions.
40. 2. A railroad crossing signaling apparatus comprising a set of bell-crank-levers positioned at each side of said crossing and adapted to be operated by a strike-arm positioned on a passing train; a rack-gear actuated by each of said bell-crank-levers; a pull-rod running parallel to the railroad track and having at each end a rack to be engaged by one of said rack-gears; electrical switching means operated by said pull-rod adapted to open and close an electrical circuit to an electric-bell, an electric motor and lights; mechanical means also actuated by

said pull-rod and adapted to operate a visible warning signal; said sets of bell-crank-levers being disposed to rotate simultaneously and in opposite directions, and means to limit the amount of rotation of said bell-crank-levers.

3. A railroad crossing signaling apparatus comprising a set of bell-crank-levers positioned at each side of said crossing and adapted to be operated by a strike-arm positioned on a passing train; a rack-gear actuated by each of said bell-crank-levers; a pull-rod running parallel to the railroad track and having at each end a rack to be engaged by one of said rack-gears; electrical switching means operated by said pull-rod adapted to open and close an electrical circuit to an electric-bell, an electric motor and lights; mechanical means also actuated by said pull-rod and adapted to operate a visible warning signal; means to hide said warning signal from view when in inoperative position; said sets of bell-crank-levers being disposed to rotate simultaneously and in opposite directions, and means to limit the amount of rotation of said bell-crank-levers.

4. A railroad crossing signaling apparatus comprising a set of bell-crank-levers positioned at each side of said crossing and adapted to be operated by a strike-arm positioned on a passing train; said strike-arm being adapted to fold backwards when striking an unyielding obstacle; a rack-gear actuated by each of said bell-crank-levers; a pull-rod running parallel to the railroad track and having at each end a rack to be engaged by one of said rack-gears; electrical switching means operated by said pull-rod adapted to open and close an electrical circuit to an electric-bell, an electric motor and lights; mechanical means also actuated by said pull-rod and adapted to operate a visible warning signal; means to hide said warning signal from view when in inoperative position; said sets of bell-crank-levers being disposed to rotate simultaneously and in opposite directions, and means to limit the amount of rotation of said bell-crank-levers.

In testimony whereof I affix my signature.
THOMAS YELCIC.
